UNITED STATES PATENT OFFICE

2,051,388

BOOM HOIST FOR CRANES

Edward B. Nickles, Manitowoc, Wis., assignor to
Manitowoc Shipbuilding Corporation, Manitowoc, Wis., a corporation of Wisconsin

Application April 27, 1932, Serial No. 607,777

2 Claims. (Cl. 212—59)

This invention relates to cranes for handling materials by means of slings, clam shell buckets, dragline excavators and similar machines, and relates particularly to boom hoists for such machines.

A primary object of the invention is to increase the leverage with which the hoisting cable for raising and lowering the boom acts, thus reducing the stresses developed in the boom, and thereby providing: first, for the use of a boom of lighter construction and weight for a given duty; second, for handling a heavier load with a given boom; and third, providing for the use of a relatively longer boom, thus correspondingly increasing the operating range or radius of the machine.

In accordance with my invention, I attain the object thereof by shifting the hitch or anchorage of the cable for raising and lowering the boom from the top of the A-frame, or from the top of a gantry which extends a considerable distance above the top of the cab, in accordance with common present practice, to a position at the rear end of the top of the cab, and in providing a suitable support to which the boom operating cable is anchored, and which will sustain the stresses produced in the operation of said boom hoist, all as hereinafter fully described.

In the accompanying drawings, in which the invention is fully illustrated,

Fig. 1 is a side view of a crane, the boom hoist of which embodies my improved rear hitch, said crane being shown as applied in use for operating a clam-shell bucket;

Fig. 2 is an exterior rear view thereof, the boom and associated parts being omitted;

Fig. 3 is an enlarged exterior rear view thereof showing framing for anchoring my improved rear hitch, the sheathing of the cab being removed in part.

Fig. 4 is a corresponding view of the framing for said boom hoist taken from a position in front of the A-frame, all operating parts being omitted.

Fig. 4a is an enlarged fragmentary detail view on the line 4a—4a of Fig. 5.

Fig. 5 is a top plan view of the cab of the crane showing the frame for the boom hoist, the roof sheathing of the cab being omitted; and

Fig. 6 is a side view of the framing shown in Fig. 5 with the side sheathing of the cab removed.

Describing the invention with reference to the drawings, A designates the rotating platform of the crane as a whole, B the cab as a whole, C the crawler on which the platform, cab and hoisting machinery are mounted, D the boom of the crane as a whole, pivoted to the rotating platform at 1,

E a clam-shell bucket, 2 the cable for supporting and operating said bucket, 3 indicates, diagrammatically, the bucket handling drum, F the boom hoist as a whole, and 4 indicates, diagrammatically, the drum or drums for operating the boom hoist, which, as shown, is rotatably mounted on a usual A-frame designated as a whole G, said drum or drums, in accordance with usual practice, being driven from the main or jack shaft of the machine.

As regards their usual features and excepting as regards features hereinafter particularly described and pointed out, all of the foregoing parts are old and well-known and may be of any usual or desired construction and will readily be understood by persons familiar with the construction and operation of such machines without a description thereof in detail.

In accordance with the invention, the hitch for the cables 22 of the boom hoist F, instead of being made directly to the A-frame G, in accordance with usual prior practice, is made to brackets 5 mounted at the top of the rear wall b of the cab B, as shown, see Figs. 1, 2 and 6, thereby increasing the angular divergence of the boom D and the cables 22 of the boom hoist F, for a boom of given length, correspondingly increasing the leverage exerted by said cables on the boom, as will be readily understood.

In what I now consider preferable construction, the rear wall of the cab, in order to provide adequate strength, is made of boiler plate of suitable thickness, say one-half inch ($\frac{1}{2}$ ") thick and is reinforced and strengthened by suitable framing consisting, as shown, of spaced angle bars 6 riveted or otherwise secured in upright position to the rear wall of the cab, secured to the upper ends of which by gusset plates 7 are spaced parallel frame members 8 and crossed frame members 9, the front ends of the members 8 being secured directly to an angle 10 forming part of the A-frame, by clips or angles 11, as shown, and the front ends of the cross members 9 being secured to the members 8 adjacent the angle 11, by gusset plates 12.

As shown, the members 8 may be described as special channels, being built up and consisting of two angles 13 and 14, flanges of which are riveted or otherwise rigidly secured together with their other angles projecting outwardly in the same direction. Also, the crossed frame members 9 consist of angles, a flange of one of which is secured to the top sides of the gusset plates 7 and 12 and of the other, to the undersides of said gusset plates, whereby the attached sides

of said cross members will be in substantially parallel planes and will be spaced a distance apart equal to the thickness of said gusset plates.

As shown, also, the angles **9** are rigidly connected together where they cross each other by a washer **15** riveted or otherwise rigidly secured to said angles.

The unconnected flanges of said crossed members **9** extend away from each other, as shown, and will form webs which will impart great strength to the frame structure of which they are constituent parts.

The top covering of the cab is made of sheet steel of suitable thickness—say No. 10 gauge—the edges thereof being bent downwardly over the sides and ends of the cab and rigidly secured to the side and end plates thereof, as by riveting or welding.

As shown, also, the top covering of the cab is connected to the front and rear end walls by angles **16** shaped to fit into the angles at the junctures of said top and said front and rear end walls, flanges of said angles being secured to said top covering and front and rear end walls. Also, as shown, the top covering of the cab is reinforced and strengthened by a transverse angular member **17**, one flange of which is secured to said roof covering and the other of which extends at right angles thereto. Said transverse member is not continuous, however, but is divided into separate sections by the reinforcing members **8**.

In accordance with my invention, also, the bracing for the rear wall **b** of the cab also comprises diagonal hog-bars **18**, opposite ends of which are connected to and which rigidly connect angle plates **19** anchored, respectively, to the platform **A** and the rear wall **b** of the cab, and to depending flanges **20** formed on the gusset plates **12**, as best shown in Figs. 4a and 6, flanges on the lower edges of the angle plates **19** being bolted to the platform **A**, and flanges on their rear edges being riveted or otherwise secured to angles **21**, a flange formed on each of which is riveted or otherwise secured to the rear wall **b** of the cab.

In accordance with common practice, also, the boom hoist **F** comprises two hoisting cables **22**, each anchored to a separate bracket **5** by sets of straps **23**, being shown as adjusted to a sheave **24** rotatably mounted between the outer ends of said pairs of straps, respectively, said straps being of such length that when they are turned into their lowermost position—defined by contact with the top of the cab—the sheaves **24** will be positioned in front of the cab so that they will be free to rotate in all operative positions of

the boom. As shown, also, each of the cables **22** is secured to an eye-hitch **25** mounted at the ends of straps **26** connected to the free end of the boom **D** by an equalizer **27**, in a familiar manner.

While I have shown and described what I now consider the preferable embodiment of the invention, particularly as regards the bracing for reinforcing and supporting the back wall of the cab, this admits of a wide range of modification and variation within the scope and contemplation of the invention.

For example, the bracing shown for reinforcing and strengthening the rear wall of the cab to withstand the stresses to which it will be subjected in use, is only one of many forms of bracing which might be devised for the purpose and exemplifies any desired or approved form of bracing, of which, in practice, there probably would be as many different designs as there might be 20 designers.

An important advantage of my invention over the usual gantry construction is the low clearance height of the machine with a boom lowered when passing under over-head obstructions.

I claim:

1. In a machine of the type specified, the combination of a platform, a cab thereon, a boom pivoted to said platform, operating mechanism mounted on said platform, including hoisting means for turning the boom pivotally to raise and lower the free end thereof, comprising a hoisting cable or cables anchored to the top of the rear wall of the cab, and means for reinforcing the rear wall of the cab to withstand the stresses to which it will be subjected in use, comprising a frame secured in fixed position to the platform of the machine at a distance from said rear wall, and bracing which connects said frame with the rear wall of the cab.

2. In a machine of the type specified, the combination of a platform, a cab thereon, a boom pivoted to said platform, operating mechanism mounted on said platform, including hoisting means for turning the boom pivotally to raise and lower the free end thereof, comprising a hoisting cable or cables, anchored to the top of the rear wall of the cab, a frame secured in fixed position to the platform of the machine, bracing which connects said frame with the rear wall of the cab, and a diagonal bar or bars the rear ends of which are anchored to the platform of the machine and to the rear wall of the cab adjacent its lower end, and the front ends of which are anchored to the frame adjacent its upper end.

EDWARD B. NICKLES.
